UNITED STATES PATENT OFFICE.

ALBERT B. MUELLER, OF RUNGE, TEXAS.

CYLINDER PROTECTOR.

Original application filed July 5, 1923, Serial No. 649,556. Divided and this application filed June 26, 1925. Serial No. 39,775.

To all whom it may concern:

Be it known that I, ALBERT B. MUELLER, a citizen of the United States, and resident of Runge, in the county of Karnes and State of Texas, have invented certain new and useful Improvements in Cylinder Protectors, of which the following is a specification.

This invention relates to protectors especially adapted for use in shallow and deep well cylinders or working barrels, and this application is a division of my application filed July 5, 1923, Serial No. 649,556 to which reference is made for a fuller explanation of application and advantages of the present invention.

An important object of this invention is to provide reliable means for preventing the accumulation of fallen rust, scale, sticks, etc., in the working barrel and consequently interfering with the operation of the plunger therein, the said means being located in the tubing at a point above the working barrel and being perforated or formed with a series of openings to provide a means whereby the oil or water, as the case may be, may be expeditiously pumped out of the well.

Furthermore the invention aims to provide simple means for preventing foreign matter, such as sand, from being pumped up into the working barrel and causing the cups and the interior of the working barrel to wear rapidly.

A further object of the invention is to provide a protector of the character specified which is of highly simplified construction, cheap to install and durable in use.

Other objects and advantages will be apparent during the course of the following description.

In the accompanying drawing forming a part of this application and in which like numerals are employed to designate like parts throughout the same,

Figure 1 is a side elevation of a protector adapted to be arranged above the working barrel and interposed in the tubing,

Figure 2 is a sectional view through the protector illustrated in Figure 1,

Figure 3 is a vertical sectional view through a working barrel adapted for connection at its upper end to one of the protectors,

Figure 4 is a side elevation of a modified

form of protector adapted to be arranged above the working barrel so as to protect the working barrel and the cups therein from falling rust and the like, and

Figure 5 is a vertical sectional view through the protector illustrated in Figure 4.

The protector illustrated in Figures 1 and 2 consists of a tube 80 the lower portion of which has connection with a nipple 81 adapted to be threaded into the cap 82 of the working barrel 83. It is thus seen that the protector 80 is located above the working barrel 83 and consequently prevents falling matter from entering the working barrel.

Referring again to Figures 1 and 2 it will be seen that a small tube 84 is arranged within the protector tube 80 and is formed with a series of openings 85 for the free passage of the oil. A screen 86 is extended about the small tube 84 and the openings 85 therein so as to effectively strain the liquid and to prevent foreign matter from dropping through the openings 85.

In carrying out this form of the invention a sucker rod 88 is passed through the tube 80 and a gland 89 carried by the upper portion of the small tube 84. A reducing member 91 is threaded onto the tube or barrel 80 and is adapted for connection with the lower portion of the tubing.

When the nipple 81 is threaded into the cap 82 the protector barrel 80 and the working barrel form a rigid construction below which a strainer member 94 is located and of course the lower portion of the strainer member 94 may be closed by means of a closure 96 similar in construction to the members 70, 72 and 73.

A modified form of protector is illustrated in Figures 4 and 5 wherein the outer protecting tube 100 has its upper end provided with a cap 101 adapted to be threaded onto the tubing and the lower portion of the outer protecting tube is provided with a cap 102 with which a nipple 103 is connected. The nipple 103 is in turn threaded onto the cap 82 so as to mount the protector above the working barrel. A sucker rod 105 is extended through a perforated tube 106 arranged within the protector barrel and terminating substantially below the upper end of the same. The tube 106 is formed with a series of diagonal incisions 107 formed by

sewing or otherwise. The upper portion of the tube 106 is formed with a cap 110 with which a threaded collar 111 is engaged and the said cap forms a means to hold the flange 112 in position, which flange acts to guide the sucker rod 105 and prevent the entrance of material into the tube 106. It will be seen that the improved protector forms an efficient means for preventing objects 10 from lodging on the cups and interfering with the operation of the same. The inventive idea involved in this application may be carried out in shallow or deep well cylinders of any size, construction or arrangement.

In operation, various types of screens and strainers may be employed to combat sand, clay and rust and to protect the parts of the working barrel and the cup leathers. 20 The openings in the various strainers may be either large or small according to the formation within which the same are located and the gravity of the fluid pumped.

The foregoing illustrates that this invention is capable of a wide variety of mechanical expressions and it is therefore to be understood that such minor changes in arrangement and construction of parts may be made as will remain within the spirit of

the invention and the scope of what is 30 claimed.

I claim:

1. A protector for well equipment comprising an outside protector tube, the ends of which are provided with reducers, a perforated strainer member arranged within the outside protector tube and having threaded connection with one of said reducers, a gland having connection with said tube and adapted for the reception of the 40 sucker rod, and a nipple connected to one of said reducers and adapted for connecting the outside protector tube to the upper portion of a working barrel.

2. A protector for well equipment comprising an outside protector tube, the ends of which are provided with reducers, a perforated strainer member arranged within the outside protector and having threaded connection with one of said reducers, a 50 gland having connection with said tube and adapted for the reception of a sucker rod, and a nipple connected to one of said reducers and adapted for connecting the outside protector tube to the upper portion of 55 a working barrel, said tube being provided with a series of diagonal incisions.

ALBERT B. MUELLER.
